UNITED STATES PATENT OFFICE.

GEORGE WILLIAMS GIBBS, JR., OF ATLANTA, GEORGIA.

EXPLOSIVE-ENGINE.

No. 882,942.

Specification of Letters Patent. Patented March 24, 1908.

Application filed November 15, 1907. Serial No. 402,387.

To all whom it may concern:

Be it known that I, GEORGE WILLIAMS GIBBS, Jr., a citizen of the United States, residing at Atlanta, county of Fulton, State of Georgia, have invented certain new and useful Improvements in Explosive-Engines; and I do hereby declare the following to be a full, clear, and exact description of the invention, such as will enable others skilled in the art to which it appertains to make and use the same.

The invention relates to explosive engines and more particularly to engines of the two-cycle type, and has for its object to provide an engine of the character described, of greatly simplified construction, increased economy and reliability of operation, its object being attained by the construction and arrangement of parts hereinafter described, by means of which scavenging of the power cylinder is effected by pure air forcibly injected into the cylinder before the admission of the fuel thereto, the air being admitted to the cylinder near the end of the power stroke of the piston and serving to drive the burned gases completely from the cylinder through an exhaust valve located at the rear end of the cylinder.

In the accompanying drawings, Figure 1 is a sectional elevation of a simple form of engine involving the invention; Fig. 2 is a plan view of the apparatus, parts of the same being shown in horizontal section.

Referring to the drawings, *a* indicates the power cylinder conveniently formed as a casting having a hollow bore of uniform diameter throughout, and a removable cap or cylinder head *a'* at the rear end thereof, which is provided with an exhaust conduit *g* to admit of the escape of the products of combustion. Attached to the lower part of the cylinder is the crank casing *o*, which is closed by a cap *o'*, said casing being constructed as an air-tight closure to provide a chamber in which compression may be effected during the power stroke of the piston.

Projecting rearwardly within the power cylinder *a* is a coaxial sleeve *b*, which may be conveniently formed as an integral part of the crank casing attached to the lower end of the power cylinder *a*, said sleeve forming with the latter an annular chamber *d* which is therefore of the same diameter as said power cylinder. According to my invention the annular chamber *d* is designed to serve as a compression chamber for fuel or air,

and to effect this purpose I provide a hollow trunk piston *c* having substantially cylindrical walls *c'*, the outer surface of which engages the inner surface of the power cylinder *a* and the inner surface of which engages the outer surface of the coaxial sleeve *b*, thereby causing the cylindrical body portion of said piston to serve as an auxiliary piston operating in the annular chamber *d* to compress the fuel or the air. In the form of the invention illustrated, the annular chamber *d* receives the fuel which is admitted thereto by means of a suitable inlet *e*, which, of course, will be provided with the usual form of check valve. To convey the gaseous fuel, which has been compressed in the annular chamber, to the power cylinder, I preferably provide a series of conduits *f* formed in the walls of the cylinder, opening at one end into the said annular chamber and at the other into the explosion chamber of the power cylinder *a* through ports *f'* near the forward end of the piston travel.

Air in appropriate quantities is admitted to the crank casing *o* through a suitable inlet *s*, which is likewise provided with an appropriate check valve, and communication is established between the crank casing and the explosion chamber of the power cylinder *a* by ducts *q* formed similarly to ducts *f*, said ducts *q* opening at one end into the crank casing and at the other through ports *p* into the explosion chamber near the forward end of the piston travel and a small distance to the rear of ports *f'*.

The piston *c* is provided with the usual form of connecting rod *l*, which in turn is connected with the crank shaft *m* suitably journaled in the crank casing. The exhaust valve *h* may be operated by any appropriate means, as illustrated, a simple and common form of apparatus for this purpose consists of rocker arm *i* pivoted in a suitable bracket projecting from the cylinder head and connected by rod *j* with a cam *k* on the crank shaft.

Suitable packing *x* is applied in the walls *c'* of the piston *c* and, similarly, packing *y* is applied to the outer face of sleeve *b*.

The operation of the engine, as described, is substantially as follows: During the rearward movement of the piston *c*, gaseous fuel is drawn into the annular chamber *d* by way of inlet *e*, and at the same time a charge of air is sucked into the crank casing *o* through inlet *s*. The charge, which had been pre-

viously admitted to the explosion chamber in cylinder *a*, is compressed by the rearward movement of the piston and at an appropriate time exploded, as will be well understood. As soon as the piston begins its forward or power stroke, the check valves in inlets *e* and *s* are closed and the advance of the piston *c* compresses the gaseous fuel in annular chamber *d* and the air in crank casing *a*. As the piston approaches the end of its forward travel, it first uncovers ports *p* and establishes communication between the crank casing *a* and the interior of the cylinder behind the piston. Just previous to this action, exhaust valve *h* is opened to permit the exploded gases to escape, and the opening of exhaust valve *h* quickly reduces the pressure of the gases to that of the atmosphere. The uncovering of the ports *p* permits the air, which has been compressed in crank casing *a*, to rush through passages *q* and ports *p* into the explosion chamber with great force, driving the remaining products of combustion longitudinally of the cylinder and out of exhaust port *g*, thereby completely scavenging and cleaning the cylinder. Shortly after the ports *p* have been opened, piston *c* uncovers ports *f'*, which establishes communication between the explosion chamber of the cylinder *a* and the annular compression chamber *d*, and admits the compressed gaseous fuel to the explosion chamber, said fuel rushing into the cylinder and reinforcing the scavenging effort of the air from crank casing *a*. The piston then begins its rearward stroke and ports *f'* and *p* are closed successively, the mixture of air and fuel in the explosion chamber is compressed and ultimately exploded, and the operation repeated. It is to be particularly noted, however, that the air from the crank casing is admitted at a point where it is most effective in driving out the burned gases, namely, near the end of the forward stroke of the piston and between the piston and the bulk of the products of combustion, the pressure of which has been reduced by the opening of the exhaust, so that they are quickly and effectively expelled from the cylinder by the ejector-like action of the air which, in turn, is followed up by the gaseous fuel under pressure. While some of the air may escape with the products of combustion, the arrangement is such that none of the fuel is carried out with the exhaust gases, for the reason that a thick stratum of air is interposed between the escaping gas and the entering fuel, and the exhaust valve being closed as soon as a complete scavenging has been effected, the explosion chamber is left completely filled with a mixture of pure air and gaseous fuel.

It will be apparent from the foregoing description that a thorough and effective scavenging of the explosion chamber may be

effected after each power stroke of the piston; the exhaust port being located at the rear end of the piston, the hot exploded gases will tend to escape therefrom immediately the exhaust valve is opened without diffusing with the comparatively cold air admitted from the crank casing, and by regulating the time and extent of opening of the exhaust valve, the clearing of the cylinder of the products of combustion may be effected with no appreciable loss of air and no loss whatever of gaseous fuel.

As stated, the annular compression chamber may receive the air to be compressed, and the crank casing will then receive the fuel or fuel and air, which arrangement is a mere obvious reversal of that hereinbefore more particularly set forth. Under these circumstances, the relation of ports *f'* and *p*, preferably, will be reversed, as will be understood, that is to say, ports *p* will be located nearer the forward limit of the piston travel than ports *f'*.

What I claim is:

1. In an explosive engine, the combination of a power cylinder having an exhaust port at its rear end, a valve controlling the same, a fixed coaxial sleeve in said cylinder forming a compression chamber therewith and of the same diameter thereas, a hollow trunk piston operating in said power cylinder and compression chamber, a crank casing in which compression is effected by the piston, conduits connecting the crank casing and compression chamber, respectively, with the power cylinder near the forward end of the piston travel, an inlet to the crank casing, and an inlet to the compression chamber.

2. In an explosive engine, the combination of a power cylinder having an exhaust port at its rear end, a valve controlling the same, a fixed coaxial sleeve connected to the forward end of said power cylinder and projecting within the same to form with the walls thereof an annular compression chamber of the same diameter as said power cylinder, a hollow trunk piston, the cylindrical walls of which engage the inner surface of the power cylinder and the outer surface of said sleeve, a crank casing in which compression is effected by the piston, conduits connecting the crank casing and compression chamber, respectively, with the power cylinder near the forward end of the piston travel, an inlet to the crank casing, and an inlet to the compression chamber.

3. In an explosive engine, the combination of a power cylinder having an exhaust port at its rear end, a fixed coaxial sleeve extending rearwardly in said cylinder and forming therewith an annular compression chamber of the same diameter thereas, a hollow trunk piston operating in the power cylinder, the cylindrical walls of which engage the inner surface of the power cylinder

and the outer surface of said sleeve, a crank casing in which compression is effected by the piston, passages formed in the engine casing connecting the crank casing with the power cylinder and the compression chamber with the power cylinder, respectively, near the forward end of the piston travel, an inlet to the crank casing, and an inlet to the compression chamber.

10 4. In an explosive engine, the combination of a power cylinder having an exhaust port at its rear end, a valve controlling the same, a fixed coaxial sleeve in said cylinder forming a compression chamber therewith, a hollow trunk piston operating in said power cylinder and compression chamber, a crank casing in which air is compressed by the piston, conduits connecting the crank casing and compression chamber, respectively, with the power cylinder near the forward end of the piston travel, means for admitting air to the crank casing, and means for admitting fuel to the compression chamber.

20 5. In an explosive engine, the combination of a power cylinder having an exhaust port at its rear end, a valve controlling the

same, a fixed coaxial sleeve connected to the forward end of said power cylinder and projecting within the same to form with the walls thereof an annular compression chamber, 30 a hollow trunk piston, the cylindrical walls of which engage the inner surface of the power cylinder and the outer surface of said sleeve, a crank casing in which air is compressed by the piston, a conduit connecting 35 the crank casing and power cylinder and opening into the latter near the forward end of the piston travel, a conduit connecting the compression chamber with the power cylinder and opening into the latter at a 40 point nearer the forward end of the piston stroke than the connection with the crank casing, means for admitting air to the crank casing, and means for admitting fuel to the compression chamber. 45

In testimony whereof I affix my signature, in presence of two witnesses.
